CLAIM

The ornamental design for a shoe as shown and described.

DESCRIPTION

FIG. 1 is a bottom front perspective view of a shoe showing my new design;

FIG. 2 is a bottom view thereof; and,

FIG. 3 is a bottom rear perspective view thereof.

The broken line immediately adjacent to the front of the photographic area defines the bounds of the claimed design and forms no part thereof. The broken lines and unshaded areas depicting the remainder of the shoe form no part of the claimed design.
